CLAIM

The ornamental design for the support for stemware, as shown and described.

DESCRIPTION

FIG. 1 is a plan view of the support for stemware;

FIG. 2 is a perspective view of the support for stemware; and,

FIG. 3 is a perspective view with one of the notches lifted to shape an opening.

The dotted lines and arrows in FIG. 1 signify the maximal and the minimal dimension of glasses to be used with the product.

1 Claim, 3 Drawing Sheets

FIG. 1

FIG. 2

FIG. 3
